UNITED STATES PATENT OFFICE.

JAMES THOMAS ATWOOD, OF ROCKFORD, ILLINOIS.

VACUUM CLEANING APPARATUS.

1,090,127.

Specification of Letters Patent. Patented Mar. 17, 1914.

Application filed May 2, 1911. Serial No. 624,615.

To all whom it may concern:

Be it known that I, JAMES THOMAS ATWOOD, a citizen of the United States of America, residing at Rockford, county of Winnebago, State of Illinois, have invented 5 certain new and useful Improvements in Vacuum Cleaning Apparatus, of which the following is a specification.

My invention relates to vacuum cleaning 10 apparatus.

The object of the invention is to improve apparatus of this class without changing either the general construction or principle of operation now commonly employed. I 15 attain this object by the use of certain features which when applied to coöperate with the elements of vacuum cleaning apparatus, perform important functions and add materially to the value of the apparatus 20 as a whole.

In the pneumatic cleaning of carpets, rugs and like articles, it is found that they will ordinarily withstand rough treatment, without showing wear, but delicate fabrics and 25 similar articles require more or less care in handling and it is therefore desirable, to provide for varying the flow of air and regulating it in accordance with the character of the articles to be cleaned. It is 30 further desirable in apparatus of this class, to maintain the connections and particularly the air pump, free and clear of any and all accumulation or deposit of dirt or dust particles passing through the same with the air, 35 in order to avoid clogging, choking and destructive wear between the moving parts thereof.

As it is practically impossible to avoid the presence of the finer dust and dirt particles 40 in the air passing through the pump, accurate fittings cannot be employed to advantage and to prevent leakage and loss of efficiency which would otherwise result, it is necessary to provide for sealing the pump 45 in such a manner as not in any way to interfere with its operation. Apparatus of this class being intended for household cleaning, is usually operated by persons unaccustomed 50 to handling and controlling machinery and its successful use depends largely upon the ease and convenience with which it may be employed, its freedom from complication and bewildering regulating means, etc., and provision is accordingly made for causing 55 the added features of improvement to operate automatically.

Apparatus suitable for meeting the above requirements, is illustrated in the accompanying drawings. I wish it understood, however, that I do not limit myself to the exact form or arrangement of the details shown, as various changes may be made therein or the features of improvement applied to other types of apparatus, without departing from the spirit and scope of the present invention.

In the drawings: Figure 1 is a view in elevation with parts shown in section, illustrating the application of my improvements, and Fig. 2 is a detail sectional view of the 70 pump and connections.

Referring now to the drawings, 1 represents a liquid containing tank or receptacle, which may be of any desired form but is preferably given the shape of a chambered 75 base casting, suitable for containing a body of liquid 2. An inlet opening is provided at 3, which is hooded by means of a coöperating deflector 4, to direct the incoming flow in the direction of or against the adjacent 80 end wall of the tank, for a purpose to be later on described. At 5, above the surface of the liquid, and near the end of the tank opposite the inlet opening, there is an air outlet, direct to the atmosphere and 7 is a 85 drain, through which the liquid, together with all matter settling in the bottom of the tank, may be drawn off. Windows 8 are provided in each end of the tank, through which the condition of the liquid may be 90 observed.

A pump 9, preferably of the rotary type, is mounted upon the tank and is connected to deliver through the inlet opening 3 thereof. The pump is driven by a motor 10, also 95 mounted on the tank. Leading to the inlet side of the pump, there is a suction connection consisting of two sets of connections, one for air and the other for liquid. The air connections comprise a main line of piping 11, which may extend to any number of the floors of a building, such main line having connections 12, at each floor which terminate in any form of "vacuum" cleaning tool 13. Under the action of the pump, atmospheric air, laden with dust and dirt particles is drawn in through the cleaning tool and passes by way of the connection 12, to the main line of piping 11, by which it is delivered into a suitable dry dust collector 14 where the coarser particles of dust and dirt are caught and held. From the 100 105 110

22

dust collector, the air, charged with the finer dust particles, goes direct to the pump through a pipe 15, which discharges it into the tank, and after being there relieved of practically all contained remaining dust particles, as in well known vacuum cleaning apparatus, escapes through an outlet opening to the atmosphere. The liquid connection consists of a pipe 16 leading from a point near the bottom of the tank to the air pipe 15. Through this connection 16, the liquid is drawn from the tank to the inlet side of the pump, by the action of the pump and after passing through the same, is returned to the tank, being discharged with the air through the inlet opening thereof. The connection 16, may be of such diameter as to render the flow of air through the pump ineffective for cleaning purposes and in order to regulate and control the quantity of liquid passing, a valve 17 is provided in the pipe, which may be set to adapt the flow of air to the character of the articles to be cleaned. The liquid in passing through the pump acts to free it of all accumulation of dust and dirt particles carried in by the air and at the same time increases the efficiency of the pump, by sealing it against leakage. The discharge from the pump into the tank meets the deflector at the inlet opening thereof and by it is directed against the end wall, in a direction opposite to the air outlet, above described, and a separa-

tion of the air and the liquid follows as a result of breaking up and spreading the discharge so that very little, if any, liquid is carried outward with the escaping air. The tank being practically closed to the escape of sound, the deflector co-acts therewith and serves the further purpose of muffling the discharge, thus doing away with the noise, which is one of the most objectionable features in the use of vacuum cleaning apparatus for household work.

The method of operation and the many important advantages of my invention will be apparent from the foregoing description.

Having, therefore, described my invention, I claim:

In a vacuum cleaning system, a suction member provided intermediate its ends with a dust collector, a liquid containing chamber open to the atmosphere, a pump interposed between the suction member and the chamber and discharging air from said suction member into said liquid containing chamber, and a suction connection from said liquid containing chamber to a point in said suction member between the dust collector and the inlet side of said pump.

In testimony whereof, I affix my signature, in the presence of two witnesses.

JAMES THOMAS ATWOOD.
